UNITED STATES PATENT OFFICE.

PERCIVAL W. JONES, OF WARWICK, RHODE ISLAND, ASSIGNOR TO ROSENHEIM CO. INC., OF PROVIDENCE, RHODE ISLAND, A CORPORATION OF RHODE ISLAND.

BRACELET.

Application filed March 28, 1927. Serial No. 178,875.

This invention relates to an improved construction of bracelet or chain formed of a plurality of units flexibly connected together, each unit comprising a box link and a slide link movable relative thereto; and the object of this invention is to provide a detachable connection between the slide link of one unit and the box link of the next unit by means of a pin which may be removed from operating position after a rotation relative to one of the links which it connects.

A further object of the invention is the provision of a connecting pin having a head at one end to engage one wall of one of the links and threaded at the other end to threadingly engage the opposite wall of the link, the pin being detachable by rotation relative to the link and accessible at one of its ends for such rotation.

With these and other objects in view, the invention consists of certain novel features of construction, as will be more fully described, and particularly pointed out in the appended claims.

In the accompanying drawings:

Figure 1 is a perspective view of two of the units of my bracelet connected together, parts being broken away to show the internal construction.

Figure 2 is a perspective view of the slide link.

Figure 3 is a perspective view of the box link.

Figure 4 is a central sectional top view showing two of the units connected together.

Figure 5 is a central sectional side view of the same.

Figure 6 is a top plan view partly in section showing two of the links connected together with a slightly modified construction.

Figure 7 is a sectional end view on line 7-7 of Figure 6.

Figure 8 is a top view partially in section showing a still further modified form of construction.

Figure 9 is a sectional end view on line 9-9 of Figure 8.

It is found in the practical construction and operation of bracelets of the type formed of a plurality of extendible units flexibly connected together, desirable to so connect the units that they may be detached one from the other by slight manipulation without the use of special tools; and in order to accomplish this in a simple and practical

way, I have mounted a pin having a head to engage one of the walls of the box link and at the same time extend through pierced openings in the walls of the slide link of the adjacent unit to connect the slide link and the box link so that they may be detached by simply unrotating the pin at one of its ends; and the following is a detailed description of the present embodiment of this invention and showing one means by which these advantageous results may be accomplished.

With reference to the drawings, 10 designates the box link having a top wall 11 folded to provide side walls 12, and bottom wall 13. Within this box link there is mounted a slide link 14 having a top wall 15, side walls 16 with an end wall or abutment 17 between which is the end wall or abutment 18 of the box link a spring 19 acts to normally hold the slide link contracted and housed within the box link 12. The side walls of the box link are extended to provide ears 20 and 21, the ear 20 being countersunk as at 22 to receive the correspondingly-shaped head 23 of the connecting pin 24 which is threaded as at 25 to engage with the internal threads 26 in the opening in the ear 21, the pin being removable by means of a screw driver or the like engaging the slot 27 in the head. The pin 24 extends through pierced openings 28 in the ears 29 of the slide link of the adjacent unit which may be easily detached from the box link 12 to which it is connected by removing the pin as above described. In some instances it is found desirable to thicken the wall having the threaded opening as illustrated at 29 in Figures 6 and 7, this being accomplished by utilizing the burr of the stock in piercing the opening or by suitably striking the stock so as to draw the stock to the position to receive additional threads in the pierced opening to assist in holding the threaded pin in position. The symmetrical appearance of the units is preserved by raising corresponding projections on the outer surface of the opposite wall of the box link, as illustrated in Figures 6 and 7 which also provides a greater bearing for the end of the pin.

In certain cases where it is undesirable to raise projections on the outer surface of a unit an effective thickening of the walls may be provided by turning inward the

stock of the end wall as illustrated at 30, in Figure 8, which serves to increase the bearing for the pin which also may be provided with additional threads for accomplishing a more secure holding of the pin in position. The threaded portion 25 at the end of the pin 24 is reduced from the adjacent portion of the pin to form a shoulder 32 to engage the inner surface of the wall of the outer box link to prevent the walls being unduly drawn together.

From the foregoing it will be seen that I have provided an extremely simple means between the slide link and the box link of the next adjacent unit to detachably connect similar units together which may be easily detached one from the other for regulating the effective working length of the bracelet.

20 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An extensible chain structure comprising a series of units, each comprising a box link and a slide link therein, and means for detachably connecting the slide link of one unit to the box link of the next unit including a pin extending through the slide link and into the box link, said pin being

provided with means whereby it is interlocked with the box link by rotary movement.

2. An extensible chain structure comprising a series of units, each comprising a box link and a slide link therein, means for detachably connecting the slide link of one unit to the box link of the next unit including a pin having threaded engagement with one of the links, and means for limiting its endways movement.

3. An extendible chain structure comprising a series of units, each comprising a box link and a slide link therein having corresponding side walls, a pin having a head engaging one of the side walls and in threaded engagement with the other side walls of the box link and extending through the side walls of the slide links to pivot and connect the links together, said pin being removable by manual manipulation of said head.

4. An extendible chain structure comprising a series of units, each comprising a box link and a slide link therein having corresponding side walls, a pin having threaded engagement with the side walls of one link and extending through the side walls of the other link, the wall having threads therein being thickened at the point of threaded engagement.

In testimony whereof I affix my signature.

PERCIVAL W. JONES.
